BOAT LAUNCHING APPARATUS

Filed Oct. 20, 1922

FIG. 1.

FIG. 2.

FIG. 3.

Inventor

GEORGE WRIGHT

By his Attorney

Ed. W. Wright

UNITED STATES PATENT OFFICE.

GEORGE WRIGHT, OF OAKLAND, CALIFORNIA.

BOAT-LAUNCHING APPARATUS.

Application filed October 20, 1922. Serial No. 595,706.

To all whom it may concern:

Be it known that I, GEORGE WRIGHT, a citizen of the United States, and a resident of Oakland, in the county of Alameda and State of California, have invented certain new and useful Improvements in Boat-Launching Apparatus, of which the following is a specification.

This invention appertains to an improvement in devices or gears for effecting the release of life boats and the like from the usual hoisting and lowering falls of the launching apparatus or davits of vessels at sea.

Among the principal objects which the present invention has in view, is: To provide for a comparatively simple, durable and efficient device or gear as hereinbefore characterized and which is capable of being readily and easily installed in new and old boats with equal facility; to provide for a novel means for effecting the positive and instant release of the engaged ends of the hoisting and lowering falls from the attaching members or hooks of the device or gear for the launching of a boat either before or after the latter is actually waterborne; and to provide other means for controlling the attaching members or hooks of the device or gear during the engagement therewith of the ends of the hoisting and lowering falls when it is desired or necessary to hoist a life boat into normal position on board a vessel.

With the foregoing and other equally important objects in view, the invention resides in the certain new and useful construction, arrangement and operation of parts as will be hereinafter more fully described, set forth in the appended claims, and illustrated in the accompanying drawing, in which:—

Figure 1 is a vertical longitudinal section through a conventional form of life boat or the like, and shows a preferred embodiment of the invention as installed therein and in its operative position for suspending the boat from the attached ends of the hoisting and lowering falls of the launching apparatus or davits of a vessel.

Figure 2 is an enlarged fragmentary vertical section of one end of a boat, showing the complementary end portion of the device or gear after the same has been actuated to released position, the device or gear portion being partly in section, and,

Figure 3 is a vertical transverse section taken on the line 3—3 of Figure 1.

Referring to the drawing, the numeral 10 indicates an operating shaft, journaled in bearings 11 spaced apart on the longitudinal center of the inner side of the bottom wall 60 of the hull of the boat *a*, and which is to have rocking movements imparted thereto by means of a hand lever 12. This shaft 10 may be made from solid metal stock, or of tubular metal stock to decrease the weight 65 thereof without appreciably decreasing the durability and strength, and the hand lever 12 which may also be made from either solid or tubular metal, is secured in right angular relation thereto at a desired point on the 70 same by means of a union or the like 13.

The opposite ends of the shaft 10 are arranged to project slightly beyond the outer of the bearings 11 and spaced from the adjacent ends of the boat hull *a*, and are each 75 connected, by means of a universal joint or coupling 14 to the lower end of a tubular member or shaft section 15. The tubular members or shaft sections 15 incline upward 80 and outwardly from their points of connection with the opposite ends of the shaft 10, and are journaled at their upper end portions in bearings formed by thickened cross- 85 portions 16 of bracket members secured at the inner sides of the ends of the boat hull *a*. The upper ends of the tubular members or shaft sections 15 are projected for a slight distance above the upper side of the cross-portions or bearings 16, and are slotted, as at 15', for purposes to be hereinafter 90 more fully explained.

Each of the bracket members consists of a metal casting or the like formed to provide spaced side walls 17, connected together at their lower edges by the cross- 95 portions 16, and at their outer vertical edges by a connecting wall 18 which is arranged to abut the inner side wall of the boat hull and to be secured thereto by means of bolts or the like 19. The upper ends of 100 the inner side edges of the bracket walls 17 are to provide upwardly extended reduced portions 20 (Figure 2), which are arranged to project above the plane of the gunwale 105 of the boat, when the brackets are secured in proper position substantially as shown, while the cross-portions 16 connect the walls 17 at their lower edges, as hereinbefore men-

tioned, and only at their inner half portions so as to leave spaces between the same and the inner sides of the connecting walls 18 whereby to facilitate the bolting of the 5 brackets in position.

Mounted between the reduced portions 20, of the side walls 17 of each of the brackets, is an attaching member or hook 21, which is of substantially L-shaped configuration 10 and has one leg portion engaged adjacent its free end on a pivot pin 22 carried by the portions 20, with its other leg portion of a form to provide a reduced free end, as by being tapered after the manner shown in 15 Figure 2, for passage through the slotted opening 15' in the upper projected end of the tubular member or shaft section 15 and into engagement with the bore of the latter, when the hook member 21 is swung to its 20 operative position inwardly of the boat and between the side walls 17 of the brackets. In the inoperative or released positions of the attaching members or hooks 21, the leg portions of the same, which are engaged on the pivots 22, rest on the gunwale of the boat hull *a*, while the tapered leg portions thereof project in an upward direction from the latter for the easy engagement thereover of the looped ends *b* of the hoisting and lowering falls *c*.

In the operation of the device or gear, and with the attaching members or hooks 21 disposed in their inoperative or released positions as hereinbefore explained, the looped ends *b* of the cables or ropes, forming the hoisting and lowering falls of the launching apparatus or davits of a vessel, will be engaged over the tapered leg portions thereof, when the members or hooks 21 will be 35 swung inwardly and downwardly on their pivots 22 and into their operative positions between the side walls 17 of the brackets. The free ends of the tapered leg portions of the members or hooks 21 will now be engaged in the bores of the tubular members or shaft sections 15, entering the same 40 through the slotted openings 15' at the completion of their downwardly swinging movements to fully operative positions, when the hooks or members will be locked against any and all accidental releasing movements by a turning movement being imparted to the tubular members or shaft sections 15 from the operating shaft 10, which will be 45 rocked in a desired direction for the purpose by the hand lever 12. This turning movement of the tubular members or shaft sections 15 results in the displacing of the slotted openings 15' thereof to one side or the other of the path of swinging movements of the members or hooks 21 so that the tapered ends of the latter are confined within the bores of the members or sections 15 and cannot disengage therefrom until a 50 reversed turning movement is imparted to 55

the same to again bring the slotted openings 15' back to releasing position. With the boat attached to the falls in this manner, the same is ready to be hoisted to service position on the vessel. When it is desired 60 to lower and launch a boat, the falls are manipulated in the usual manner for such purpose, and when the boat is waterborne, or nearly so, the attendant will grasp the hand lever 12 and manipulate the same to 65 impart a rocking movement to the operating shaft 10 and consequently to the tubular members or hollow shaft sections 15, whereby the slotted openings 15' will be moved into the path of movement of the attaching 70 members or hooks 21, with the result that the tapered leg portions of the latter will be free to disengage therefrom to released 75 position. If the boat be not fully waterborne at the moment of release of the attaching members or hooks 21, the weight of the same will cause the positive and instantaneous disengagement of the members or hooks which will swing upwardly on their pivots 22 to fully opened position and allow the looped ends of the falls to free 80 themselves automatically. However, should the boat be fully waterborne at the moment of release of the attaching members or hooks 21 so that there is an appreciable amount 85 of slack in the falls, then the looped ends 90 of the latter will automatically free themselves with the drift of the boat, or the same may be readily disengaged by an upward pull thereon by nearby persons. In 95 actual practice, however, this manual freeing of the looped ends *b* of the falls will 100 seldom, if ever, be found to be necessary.

To facilitate the attaching of the looped ends *b* of the falls *c* to the hooks 21, the invention contemplates the provision of hand levers 23, one cooperative with each of the hooks, whereby the same are moved to positions to hold the latter against opening or releasing movements during the 105 manipulation of the hand lever 12 for the rocking of the shafts 10 and 15 to effect the locking of the tapered leg portions of the hooks 21 in the bores of the shaft sections 15, as hereinbefore described. Each 110 of these hand levers 23 is formed to provide a forked portion 23' arranged in straddling relation with respect to the side walls 17 of a bracket and is pivoted for the necessary 115 vertical swinging movement on a pivot pin 120 24 passed through the latter. In use, after the looped ends *b* of the falls *c* are engaged over the members or hooks 21, the latter are 125 swung downwardly between the side walls 17 of the brackets until the free ends of the tapered leg portions thereof are engaged within the bores 15' of the hollow shaft sections 15, when the hand levers 23 are 130 swung upwardly until the connected portions 23'', of the forked portions 23' bind 135

against the upper connected ends of the said brackets and capable of opening and closing movements for the attaching thereto and the disengagement therefrom of the looped ends of the usual hoisting and lowering falls of a vessel, an operating shaft journalled longitudinally of the boat, tubular shaft sections coupled to the opposite ends of said operating shaft and having their upper end portions journalled in the lower ends of said brackets, the upper ends of said tubular shaft sections having slots opening into the bores thereof for the passage therethrough and engagement in the latter of the free ends of said hook members after the looped ends of the said falls have been engaged therewith, means for actuating said operating shaft for imparting turning movements to said tubular shaft sections whereby to effect the locking of the free ends of said hook members in position by the displacing of the said slots to one side of the path of swinging movement of the latter and the release of the free ends of the same for swinging movement to open position for the disengagement therefrom of the attached ends of the said falls by returning the said slots to proper position for the purpose, and forked hand levers pivotally straddling the forked arms of the brackets for temporary engagement over said hook members to retain same in closed position during the movement of said tubular shaft sections to locking position.

From the foregoing, it will be obvious that, while a preferred embodiment of the invention has been described and illustrated herein in specific terms and details of the construction, arrangement and operation of the parts thereof, various changes in and modifications of the same may be resorted to without departing from the scope of the claim appended hereto.

Having thus fully described the invention, what is claimed, is:—

In a launching gear for life boats and the like, forked brackets adapted to be mounted at the inner sides of the opposite ends of a boat, hook members pivotally mounted in

GEORGE WRIGHT.
